UNITED STATES PATENT OFFICE.

BENJAMIN B. HILL, OF SPRINGFIELD, MASSACHUSETTS.

DESIGN FOR A HAND-STAMP.

Specification forming part of Design No. 5,449, dated December 26, 1871.

To all whom it may concern:

Be it known that I, BENJAMIN B. HILL, of Springfield, in the county of Hampden and State of Massachusetts, have invented a new and original Design for a Marking-Stamp; and I do hereby declare that the following, in connection with the accompanying photograph and the letters of reference marked thereon, does give a full, clear, and exact description thereof, sufficient to enable any one skilled in the art to manufacture my invention.

The nature of my design for a marking-stamp is fully represented in the accompanying photographic illustration, to which, with the letters marked thereon, reference is made.

B is the hand piece, upon which the blow is struck. C is the piston. A is the piston-guide. D is the main body of the stamp, having the feet E. F is the type-holder, in which the type are secured, and which is attached to the lower end of the piston C.

Having thus described my invention, what I claim as new, and desire to secure by Letters Patent, is—

The design for a marking-stamp, substantially herein described and shown.

BENJAMIN B. HILL.

Witnesses:

T. A. CURTIS,
CLARENCE BUCKLAND.
